United States Patent Office

Des. 226,344
Patented Feb. 13, 1973

226,344

HANDBAG

Judith J. Loomis, 232 Lafayette St.,
Memphis, Tenn. 38111

Filed Jan. 11, 1972, Ser. No. 217,083

Term of patent 14 years

Int. Cl. D3—01

U.S. Cl. D87—3 F

FIG. 1

FIG. 2

FIG. 3

FIG. 4

FIG. 1 is a top plan view of the handbag showing my new design.

FIG. 2 is a side elevational view thereof, the handle being shown broken away to indicate indeterminate length.

FIG. 3 is a bottom plan view thereof.

FIG. 4 is an end elevational view thereof.

I claim:

The ornamental design for a handbag, as shown and described.
